UNITED STATES PATENT OFFICE.

LUCIOUS E. BRADSHAW, OF MYRTLE, MISSISSIPPI.

COLLAPSIBLE FORTIFICATION-BREASTWORKS.

1,246,228.

Specification of Letters Patent. Patented Nov. 13, 1917.

Application filed July 18, 1917. Serial No. 181,312.

To all whom it may concern:

Be it known that I, LUCIOUS E. BRADSHAW, a citizen of the United States, residing at Myrtle, in the county of Union and State of Mississippi, have invented certain new and useful Improvements in Collapsible Fortification-Breastworks, of which the following is a specification, reference being had to the accompanying drawings.

10 This invention relates to a collapsible fortification breastwork and has for its primary object to provide a device of this character which may be easily and quickly manipulated so that it will lie flat upon the ground, or can be raised and securely anchored in an upright position to afford a protection for soldiers stationed behind the breastwork.

It is another and more particular object 20 of the invention to provide a device of this character, including anchoring stakes adapted to be driven into the ground and between which the body plate of the breastwork is pivoted at one of its ends, said plate having 25 a plurality of port holes therein, revolvers swingingly mounted upon the plate for firing through the respective port holes, and means on the plate to cover and protect the revolvers when the body plate is folded 30 downwardly into engagement with the ground.

It is also another important object of the invention to provide very simple means for 35 securely anchoring the pivoted shield plate to permit of its movement to operative or inoperative position and at the same time effectually prevent any displacement of the breastwork from its anchorage.

It is another object of my invention to 40 provide a device of the above character which is simple in construction, comparatively light in weight, and over which retreating troops may move without hindrance, the shield plates being movable to their erect positions very quickly when the troops are halted to check the advance of the enemy, each breast plate being equipped with a full supply of ammunition and revolvers ready for instant use.

50 With the above and other objects in view, my invention consists in the novel features of construction, combination, and arrangement of parts to be hereinafter more fully

described, claimed, and illustrated in the accompanying drawings, in which,

55

Figure 1 is a perspective view showing my improved breastwork in its operative position;

Fig. 2 is a similar view showing the device folded or collapsed;

60

Fig. 3 is a section taken on the line 3—3 of Fig. 2; and

Fig. 4 is a section taken on the line 4—4 of Fig. 3.

Referring in detail to the drawings, 5 designates the body plate of the shield which is of suitable dimensions and preferable of rectangular form in cross-section. Marginal bars or flanges 6 project from one face of this plate along its longitudinal edges 70 and one of the end edges thereof. The other end of the plate is provided on its opposite longitudinal edges with the laterally projecting trunnions 7 which are loosely mounted for free turning movement 75 in the upper ends of the stakes 8, said stakes being retained in connection with the trunnions by means of the pins 9. The stakes 8 are of requisite length so that when driven into the ground, they will securely 80 anchor the plates against lateral shifting movement.

10 designates a front plate which is of substantially the same dimensions as the body plate 5 and is disposed in spaced parallel relation thereto. Suitable cushioning springs, indicated at 11, are interposed between the plate 10 and the body plate 5 and cushion the movement of the former when subject to the impact of projectiles, whereby the body plate is relieved of considerable shock and jar and possible injury thereto reduced to a minimum. These two plates 85 5 and 10 are formed with two series of coinciding port holes 12, the port holes in one series being disposed in staggered relation with respect to those in the other series. At opposite sides of each port hole in the plate 5 on the rear face thereof, angular bearing brackets 13 are secured, and in 95 line with each pair of brackets between the port holes in the other series, a resilient metal clip 14 is fixed to the plate. R designates the revolvers, the barrel of each being provided upon diametrically opposite 100 sides with pins indicated at R'. These pins

are rotatably engaged in the spaced bearing brackets 13. The stock of the revolver is adapted to engage between the spaced portions of the resilient clip 14, whereby the 5 revolver is held in inoperative position with its barrel in substantially parallel relation to the body plate.

Below the two series of port holes 12, a tray 15 is pivotally mounted, as at 16, between the longitudinal flanges 6 on the body plate. This tray is also provided with marginal flanges 17 to limit the inward folding movement of the tray against the rear face of the body plate. This tray is of sufficient depth to accommodate the revolvers mounted upon the body plate without exerting any pressure thereon, whereby they might possibly be damaged. The tray is adapted to be held in its folded position 20 against the body plate 5 by a spring latch plate 18 which is fixed at one of its ends to the body plate and is adapted to operatively engage a pin or stud 19 on the tray.

As an additional means for positioning 25 the body plate 5 upon the ground, I provide a metal yoke bar 20, the arms of which are pivoted at their ends, as indicated at 21, upon the side flanges 6 of the plate 5. To the intermediate portion of this yoke, a 30 bar 22 is hinged as at 23, and a leg 24 is centrally fixed to this bar at one of its ends. The other end of said leg is pivotally connected, as shown at 25, to a metal stake 26. As shown in Fig. 2 of the drawings, 35 when the body plate 5 is folded downwardly to lie flat upon the ground, the yoke arms extend in parallel relation to the side flanges on the plate and beyond one end thereof, the leg 24 folding inwardly between the 40 arms of said yoke. The end flange 6 on the body plate is centrally notched, as at 27, to accommodate said leg. In setting up the device in position for use, the stake 26 must, of course, be so located with respect to the 45 anchoring stakes 9 upon which the body plate is pivotally supported as to permit of the proper folding or collapsing movement of the body plate. The body plate may be further held in its set position against shifting movement by means of a long anchoring rod 28 which is connected by a wire 29 to a staple 30 projecting from the rear face of the plate 5.

In the use of the device, the body plate 5 is raised from its horizontal position to a vertical position, the yoke 20 swinging upwardly and forwardly with said plate until the leg 24 is moved to a forwardly and upwardly inclined position with respect to the 60 stake 26. The leg and the yoke will thus constitute a substantially rigid brace between the stake 26 and the shield plate 5. The plate will thus be sustained in its erect position, and provides a shield for two sol-

diers. The tray 16 is swung outwardly at 65 right angles to the body plate 5, and the revolvers are also disengaged from the clips 14 and positioned as seen in Fig. 1, with their barrels in alignment with the port holes 12. The tray affords convenient 70 means for supporting a large quantity of ammunition so that the magazines of the revolvers which are preferably of the automatic type, may be quickly re-loaded. If desired, suitable ammunition cases may be 75 provided on the tray to contain a complete supply of ammunition ready for immediate use, when the fortification breastwork or shield is erected. The soldiers may fire upon advancing troops by means of either row 80 of revolvers, in accordance with the formation and number of the advancing troops. When the device is not in use, the body plate 5 is folded downwardly upon the ground as seen in Fig. 2, the tray 16 having been 85 latched in its closed position over the revolvers mounted upon said plate so as to protect the latter. Thus, the device will not be in anywise injured by troops marching over the same. My invention is, therefore, 90 particularly advantageous for use during a retreat, as the troops can stop at any point where a line of these breastwork shields have been arranged, and quickly raise the shields to their operative positions and immediately fire upon the enemy by means of the loaded revolvers with which the device is equipped. The yieldable front plate 10 will effectively cushion the impact of small projectiles so that the device will not be 100 knocked over or injured during a charge. Of course, when the position is assaulted by means of artillery, the breastwork shields are in folded position and lie perfectly flat upon the ground so that large explosive 105 projectiles will not be likely to strike the same.

From the foregoing description, taken in connection with the accompanying drawing, the construction, manner of use, and several 110 advantages of my invention will be clearly and fully understood. The device is comparatively light in weight and large numbers thereof may be transported from place to place owing to the fact that the several parts of the device when folded or collapsed, are very compactly arranged. It will also be appreciated that I have devised a fortification breastwork for field troops, which can be very easily and quickly anchored in the desired position and disposed in its 120 erect position for use, or folded to an inoperative position. When it is necessary to abandon the shields in a retreat, they may be rendered useless to the enemy by simply removing the revolvers and detaching the anchoring stakes and the supporting yoke. 125 It will also be seen that the device as a whole

is exceedingly durable and may be produced in large quantities at relatively small manufacturing cost.

While I have herein shown and described the preferred construction and arrangement of the several elements, it is to be understood that the device is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:

1. A device of the character described comprising a shield plate, means for supporting the plate for vertical swinging movement, and a brace consisting of hingedly connected sections, one of said sections having a ground anchor pivotally connected thereto and the other brace section being operatively connected to the shield plate, said sections when extended sustaining the plate in a substantially vertical position, and being foldable with respect to each other, when the plate is moved to a horizontal position.

2. In a device of the character described comprising anchoring stakes adapted for engagement in the ground, a shield plate pivotally mounted between said stakes for vertical swinging movement, means pivotally connected to the shield plate to sustain said plate in a substantially vertical operative position, said means being movable with respect to the shield plate when the latter is disposed horizontally in contact with the ground to lie in the same plane with the shield plate.

3. A device of the character described comprising supporting means, a shield plate pivotally mounted upon the supporting means for swinging movement in a vertical plane, a yoke member pivotally connected to the shield plate, a foldable leg connected to the yoke member, and an anchoring stake connected to said leg, said yoke and leg in one position sustaining the shield plate in substantially vertical operative position and being foldable with respect to said plate when the latter is moved to a horizontal position.

4. A device of the character described comprising a shield plate mounted for swinging movement in a vertical plane, an ammunition supporting tray pivotally connected to the plate and foldable against one side thereof, and means pivotally connected to the plate to sustain the same in a substantially vertical operative position, said means being foldable with respect to the plate when the latter is moved to a substantially horizontal plane with respect to the ground surface.

5. A device of the character described including a shield plate having a port opening, a fire arm pivotally mounted upon one side of the plate and movable to a position to discharge projectiles through the port opening, and releasable clamping means to engage the fire arm and hold the same in an inoperative position substantially in parallel relation to the plate.

6. A device of the character described including a shield plate having a series of port openings, fire arms pivotally mounted upon one side of the plate and movable to discharge projectiles through the respective openings, and an ammunition supporting tray pivotally connected to the plate and extending at right angles thereto below the port openings to an inoperative position, said tray being foldable against the face of the plate over the fire arms.

7. A device of the character described including a shield plate having a series of port openings, fire arms pivotally mounted upon one side of the plate and adapted to be positioned to discharge projectiles through the respective openings, means on the plate to co-act with the respective fire arms and retain the same in inoperative positions substantially in parallel relation to the plate, and an ammunition tray mounted upon the plate for folding movement against the face of the plate and over said fire arms.

8. A device of the character described including a shield plate mounted for swinging movement in a vertical plane and having a series of port openings, fire arms mounted upon one side of the plate to discharge projectiles through the respective openings, an ammunition supporting tray pivotally connected to the plate to fold against the face thereof and over the fire arms when the shield plate is moved to an inoperative position and disposed substantially in a horizontal plane, and means for sustaining the shield plate in a vertical operative position.

9. A device of the character described, comprising a pivotally mounted shield plate having a series of port openings therein, an ammunition receiving tray pivotally mounted upon one side of said plate and foldable against the shield plate when the latter is swung to an inoperative position in parallel relation to the ground, and means for sustaining the shield plate in a substantially vertical operative position.

10. In a device of the character described, a shield plate, ground anchors between and upon which said plate is pivotally mounted for swinging movement, said plate being provided with angularly extending marginal walls, an ammunition tray pivotally mounted between the opposed marginal walls of the plate and movable to a position at right angles to the shield plate, when the latter

is in a vertical operative position, said tray being foldable against the face of the shield plate between the marginal walls thereof when said plate is swung downwardly to a horizontal position upon the ground, and means for retaining the tray in the latter position.

In testimony whereof I hereunto affix my signature in the presence of two witnesses.

LUCIOUS E. BRADSHAW.
